US0D1006015S

(12) **United States Design Patent** (10) **Patent No.:** **US D1,006,015 S**
(45) **Date of Patent:** **** Nov. 28, 2023**

(54) **SOLID STATE DRIVE MEMORY DEVICE**

(71) Applicant: **SAMSUNG ELECTRONICS CO., LTD.**, Suwon-si (KR)

(72) Inventor: **Gye-Jin Jun**, Suwon-si (KR)

(73) Assignee: **SAMSUNG ELECTRONICS CO., LTD.**, Suwon-si (KR)

(**) Term: **15 Years**

(21) Appl. No.: **29/796,272**

(22) Filed: **Jun. 23, 2021**

(30) **Foreign Application Priority Data**

Jan. 26, 2021 (KR) 30-2021-0004097

(57) **CLAIM**

The ornamental design for a solid state drive memory device, as shown and described.

DESCRIPTION

FIG. 1 is a front perspective view of a solid state drive memory device showing my new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof; and,

FIG. 8 is another perspective view thereof.

The evenly dashed broken lines shown in the figures depict portions of the solid state drive memory device and form no part of the claim.

1 Claim, 8 Drawing Sheets
